UNITED STATES PATENT OFFICE

95,956

DESIGN FOR A CHRISTMAS TREE LIGHTING UNIT CARTON

Mitchel E. Holy, Chicago, Ill., assignor to Container Corporation of America, Chicago, Ill., a corporation of Delaware

Application September 28, 1934, Serial No. 53,430

Term of patent 14 years

To whom it may concern:

Be it known that I, Mitchel E. Holy, a citizen of the United States, residing at 14320 South Campbell Avenue, Chicago, in the county of Cook and State of Illinois, have invented a new, original, and ornamental Design for Christmas Tree Lighting Unit Cartons, of which the following is a specification, reference being had to the accompanying drawing, forming a part thereof.

In the drawing, the figure is a perspective view of a Christmas tree lighting unit carton embodying my new and ornamental design in which

the striking features are the inwardly extending, tapering, symmetrically formed panels meeting at their apexes and forming therebetween a symmetrically shaped triangular pocket from which radiates the lamp receiving openings, the total effect being to suggest a conventional, light decorated Christmas tree.

I claim:—

The ornamental design for a Christmas tree lighting unit carton, substantially as shown and described.

MITCHEL E. HOLY.
